FEELER DEVICE FOR KNITTING MACHINES

Harvey A. Tanguay, Central Falls, R. I.

Application April 8, 1947, Serial No. 740,036

2 Claims. (Cl. 66—166)

1

This invention relates to a feeler device for knitting machines to ascertain whether there has been a dropped stitch in the cloth being formed by the knitting machine.

It is an object of the present invention to provide a feeler device wherein a long engagement of the feeler device with the back plate through the hole of the cloth will be had so as to make certain that there will be a good contact and adequate signal given to the operator of the machine so that the hole in the cloth will be more definitely indicated to the operator.

Other objects of the present invention are to make a feeler device for recording the defects in the cloth which is of simple construction, inexpensive to manufacture and efficient in operation.

For other objects and for a better understanding of the invention, reference may be had to the following detailed description taken in connection with the accompanying drawing, in which

Fig. 1 is a side elevational view of a machine having the feeler device of the present arrangement with portions broken away and shown in section so as to show the workings of the device.

Fig. 2 is a top plan view of the arrangement as shown in Fig. 1.

Fig. 3 is an illustrative view showing the location of the feeler element as the cloth is being passed by the same and just prior to it reaching a hole in the cloth.

Fig. 4 is a view similar to Fig. 3 where the feeler element has dropped into the hole and has been moved rearwardly and made contact with the metal wall of the cylinder containing the cloth.

Fig. 5 is a view similar to Figs. 3 and 4 where the feeler element has been carried by and is ready to be set again upon the cloth being examined.

Fig. 6 is a side elevational view of the support before the feeler element after the same has been extended outwardly against the action of a spring extending between the supporting arm and a fixed member.

Fig. 7 is a bottom plan view of the feeler element and its supporting members.

Fig. 8 is a bottom plan view of a fixed or top support member.

Fig. 9 is a fragmentary front elevational view of the swingable support member.

Fig. 10 is a wiring diagram connected with the feeler element showing the control circuit for stopping the machine and giving an indication.

Referring now to the figures, 15 represents a base of a machine to which a ground wire 16 is connected. Extending upwardly from the base is

5 a post 17 on which there is slidably connected a fixed laterally extending supporting arm 18. This arm is retained on the post 17 by a clamping screw 19 and can be adjusted to any desired vertical position on the post 17. To the bottom of the lateral support arm 18 there is connected a plate 21, Fig. 8, by means of a bolt 22 extended through a slot 23. This plate 21 can be adjusted to any distance beyond the end of the support arm 18 by loosening the bolt 22 and causing the plate to be moved outwardly. The outer end of the plate 21 has bifurcated portions 23 between which is extended a vertical supporting arm 24. The connection of the arm 24 with the portions 10 23 is effected by a pivot pin 25. This arm 24 can swing laterally outwardly and is returned to its lowered position by a tension spring 26 connected between a hook 27 on the arm 24 and a hook or eye formation 28 on the plate 21.

15 On the lower end of the arm, there is fastened an inwardly extending arm 29 by a screw 31. This arm 29 on its bottom face has connected to it feeler element 32 adapted to rotate across the bottom of the same and which has a feeler portion 33 thereon of rounded shape on its engaging face and curved inwardly on its opposite face so as to form a hook which will enter the hole in cloth 35 so that the feeler element 32 will be pivoted by its connection with the cloth so as to be given a prolonged engagement with a cylinder wall surface 36. When this contact is made, current will be set up in a wire circuit 37, Fig. 10, and a control element or indicator 38 will be energized either to stop the machine or to give a signal 20 to the operator. A battery 39 supplies current to this circuit.

25 The operation of the feeler element and its engagement with the surface 36, will be more clearly understood by a study of Figs. 3, 4 and 5. In Fig. 3 it will be noted that the hole is approaching the feeler portion 33. As the hole comes under the portion 33, the portion 33 will drop into the hole and will have contact with the wall surface 36. The wall surface 36 and the cloth will continue to move and the contact of the portion 33 with the wall surface 36 will be prolonged until such time as the contact or feeler element 32 has been taken by as shown in Fig. 5. The feeler element 32 is pivotally connected on the arm 29 by means of a downwardly extending pivot pin 41 to which there is anchored a coil spring 42 having its outer end anchored as indicated at 43 upon the feeler element and tending 30 to rotate the same in a clockwise direction as

viewed in Figs. 3 and 4. A stop member projecting downwardly from the arm 29 will limit the rotating movement of the feeler element. This stop member is indicated at 44. The hole in the cloth material into which the feeler element portion 33 drops is indicated at 46.

As viewed in Fig. 6, it will be noted that while the feeler element is being pivoted on the arm 29, the vertical arm 24 can be extended outwardly against the action of spring 26.

Having now described my invention, I claim:

1. A feeler mechanism for locating holes in cloth, comprising a support with a vertical member thereon, a lateral arm extending from the vertical member, a plate connected to the lateral arm, a vertically swingable member pivotally connected to the plate, means adjustably connecting said plate to said lateral arm, a feeler device connected to the bottom end of the vertically swingable member comprising a spring biased swingable feeler element having a finger formation outwardly curved on one side and inwardly curved on the other to form a hook-like formation adapted to enter a hole in the cloth, and a tension spring extending between and attached to the vertically extending swingable member and the plate for biasing the feeler device toward the hole in the cloth.

2. In a feeler mechanism for locating holes in cloth as defined in claim 1, the said feeler device including a laterally extending arm adjustably connected to the lower end of the vertically extending swingable member, a stud on said arm and on which the feeler element is pivotally mounted for angular movement in a horizontal plane, a coil spring on the stud and abutting the stud and the feeler element for urging the feeler element in one direction, and stop means against which the feeler element may abut.

HARVEY A. TANGUAY.
